UNITED STATES PATENT OFFICE.

JAY B. RHODES, OF HARVEY, ILLINOIS, ASSIGNOR TO FREDERICK C. AUSTIN,
OF CHICAGO, ILLINOIS.

SPRINKLER.

SPECIFICATION forming part of Letters Patent No. 639,289, dated December 19, 1899.
Application filed April 20, 1899. Serial No. 713,737. (No model.)

To all whom it may concern:

Be it known that I, JAY B. RHODES, a citizen of the United States, residing at Harvey, in the county of Cook, State of Illinois, have invented a certain new and useful Improvement in Sprinklers, of which the following is a specification.

My invention relates more particularly to a construction of sprinkler comprising a hollow sprinkler-head suitably connected with the water-tank of a sprinkling cart or vehicle, and having one of its ends open and provided with a sliding cap, which is laterally apertured and adjustable longitudinally relatively to the length of the head for the purpose of establishing and cutting off the flow of water and for the further purpose of varying the volume or quantity of the discharge.

The objects of my invention are to simplify the construction of the sprinkler-head and arrangement of packing for preventing leakage when the sprinkler-head is entirely closed by the cap; to provide an improved cut-off device for varying the discharge relatively and with relation to the width of the road; to provide improved means for operating both the laterally-apertured cap and the cut-off device, and to arrange said means or devices for operating the said cap and cut-off device, whereby they can be readily and easily actuated by the driver without interfering with his attention to the team, and to further adapt said means for efficient service in connection with other devices for regulating the discharge from the sprinkler-head.

In accordance with my invention the packing can be arranged between the edge or end of the hollow sprinkler-head and the flanged sleeve or ring which is screwed into the open end of the hollow head. The discharge can be established and cut off by a longitudinally-adjustable laterally-apertured cap fitted to the hollow sprinkler-head, and this cap can be operated by a hollow rod or sleeve which extends through the hollow sprinkler-head. The cut-off is arranged upon the cap and is connected with and operated by a rod which extends through the said sleeve. Through the medium of power-operating devices, hereinafter set forth, the cut-off can be adjusted independently of the cap and the cap and

cut-off as a whole can be moved in a direction parallel with the axis of the rod and sleeve for the purpose of establishing or cutting off the flow of water. Within reach of the driver is a lever from which the sleeve can be adjusted through the medium of suitable power-transmitting means or connection, and upon said lever is a treadle or foot-rocker, which can be operated independently of the lever for the purpose of adjusting the cut-off.

Various other details serving to increase the general efficiency of the sprinkler are hereinafter more fully set forth.

In the accompanying drawings, Figure 1 is a side elevation of a sprinkling cart or vehicle with my improvements applied thereto. Fig. 2 shows said cart or vehicle in front elevation, and Fig. 3 shows the same in rear end elevation. Fig. 4 is a top plan view of the sprinkling-head and cut-off. Fig. 5 is a section taken centrally and longitudinally through Fig. 4. Fig. 6 is a section taken transversely through the sprinkling device on line xx in Fig. 5. Fig. 7 is a like view on line yy in Fig. 5. Fig. 8 shows the rear end portion of the sprinkling device in Fig. 5, with the laterally-apertured cap moved back so as to establish the flow of water. Fig. 9 is a detail showing in perspective the devices from which the cap and cut-off are actuated. Fig. 10 shows the sprinkling device in perspective and illustrates a portion of the power-transmitting devices or connections. Fig. 11 illustrates a rack whereby the lever H can be locked by the driver.

The cart or carriage A can be of any ordinary or suitable construction, and the water-tank B can be mounted thereon in any suitable or desired way. A sprinkling device is arranged at each side of the rear end of the cart or carriage, and as the two sprinkling devices illustrated are preferably of relatively like construction a description of one will answer for both.

The construction of sprinkling device shown comprises a hollow cylindric head C , suitably supported from the vehicle-body and having its forward end portion connected with the tank by a supply-pipe 1. The discharge from the sprinkler-head C is effected through a laterally-apertured cap D , fitted and arranged

to slide longitudinally upon the rear end portion of the sprinkler-head, an effective arrangement being to provide the cap with perforations 2, which serve as discharge ports or outlets. By such construction the cap can be shifted back to an extent to open all or a portion of its discharge-openings and in alternation therewith shifted forward to an extent to permit its discharge-openings to be closed by the sprinkler-head. While the longitudinal adjustment of the cap will serve to vary the volume of the discharge and determine the thickness, so to speak, of the sheet of spray, it is also desirable to vary the width 15 of such sheet of spray relatively to the width of the road. To such end the ports or perforations in the cap can also be more or less closed or opened by a cut-off E, arranged for adjustment in a direction transverse to the line of longitudinal adjustment of the cap. In this way while the longitudinal adjustment of the cap will vary the width of its discharge-port capacity relatively to the line of progression of the vehicle the relatively 20 transverse adjustment of the cut-off will vary the width of such discharge-port capacity transversely to such line of progression. As a simple arrangement the cut-off may comprise a curved plate fitted to slide upon the cap in directions transverse to the length of the cap and provided with some suitable stop device, such as a spring 3, confined within a socket in or on the plate and arranged to bear upon the cap and a set-screw 4 for varying 25 the compression of the spring. The cut-off can be conveniently operated by the driver of the vehicle, and to such end it is formed with or attached to a bent arm 5, arranged to swing over the rear end portion of the cap 30 and secured to a rock-shaft 6, which extends forwardly through the sprinkler-head. The rear end of this rock-shaft extends through the closed end 7 of the cap, and one end of the arm 5 can be held upon such rear end of the rock-shaft by a nut 8 or other suitable 35 securing device. To prevent leakage and also permit the cut-off to be easily operated, the rod or rock-shaft 6 extends through a hollow rod or sleeve F, which latter extends from the closed end of the cap to and through the forward end of the sprinkler-head, thereby preventing exposure of the rod or rock-shaft to the water within the sprinkler, and hence avoiding leakage. This sleeve also provides 40 a means for longitudinally adjusting the cap, and to such end it is arranged for longitudinal adjustment. As a desirable arrangement the longitudinally-adjustable sleeve F is at its rear end screwed into a threaded opening 45 through the closed end of the cap, while its forward end portion is arranged to work through a stuffing-box 9 at the forward end of the sprinkler-head. The sleeve F provides a bearing for the rock-shaft 6, which latter 50 while adapted to turn independently of the sleeve for the purpose of adjusting the cut-off is also capable of longitudinal movement

synchronously with the sleeve, when the latter is adjusted longitudinally for the purpose of adjusting the cap. This construction also 70 enables me to do away with all need for internal supports for the sleeve and permits a simple arrangement of packing device herein comprising an externally-threaded ring G, screwed into the internally-threaded rear end 75 of the sprinkler-head and provided with an annular flange 10, which abuts against an annular packing 11 and compacts the same against the rear end of the sprinkler-head when the ring is suitably adjusted. With such 80 arrangement the cap may contain a packing 12, which will be drawn against the rear edge of the ring when the cap is adjusted to close the discharge.

As a means for adjusting the cap to open 85 or close or vary the discharge I provide at the forward end of the cart or carriage a vibratory lever H, under control of the driver and connected with the longitudinally-movable sleeve F by power-transmitting connections. I also provide this lever with a supplemental device which is connected with the longitudinally-movable rock-shaft 6 by power-transmitting connection, whereby the rock-shaft can be rocked about its axis when 90 it is desired to adjust the cut-off, the general arrangement being such that when the lever H is operated both the sleeve F and the rock-shaft 6 will move longitudinally in unison. The lever H is desirably a foot-lever extending 95 up through the foot-board I of the cart or carriage and having its upper end provided with a rocking foot-piece or foot-rocker K, which latter can be operated independently 100 of the foot-lever H for the purpose of adjusting the cut-off E.

As a simple and efficient power-transmitting connection between the lever H and the sleeve F, which is secured to the apertured cap, the end portion of such sleeve, which extends 110 out from the forward end of the sprinkler-head, is connected with a swinging arm 13, pivoted to the cart or tank and hinge-connected with said sleeve. The swinging arm 13 is in turn connected with a short transversely-arranged rock-shaft 14 at the forward end of the cart by a pitman or connecting-rod 15, having its forward end connected with an arm 16 on the rock-shaft 14. The lever H is fixed upon the rock-shaft 14, and hence a 115 forward-and-back swing on the part of the lever H will, through the medium of the power-transmitting mechanism described, cause the longitudinal adjustment of the cap D.

As a means for operating the cut-off E from 120 the treadle or foot-rocker K the rock-shaft 6, which carries the cut-off arm 5 and which extends through the cap-operating sleeve F, has its forward end extended beyond the forward end of sleeve F and provided with an arm or 130 crank 17. This arm or crank 17 is connected with a hollow rock-shaft or rock-sleeve 18 on the rod 15 by a pitman or connecting-rod 19, having at one end a sliding pivotal connec-

tion with the crank-arm 17 and having at its opposite end a rigid connection with the rear end of the rock-sleeve 18. The forward end of the rock-sleeve 18 carries a crank-arm 20, which connects with the foot-rocker by a rod 21 or like connection, in which way, when the foot-rocker is operated independently of the lever H, the rock-sleeve 18 will be turned upon rod 15 and in so doing will cause the rock-shaft 6 to have a like movement. When, however, the lever H is swung either forward or back, the rock-sleeve 18 and rod 15 will both move longitudinally, and the sleeve F and rock-shaft 6 will have a like movement. Any suitable connection can be used to permit the rock-sleeve 18 to turn independently of rod 15, but compel it to move with such sleeve when the latter is shifted longitudinally, and likewise any suitable connection can be employed to permit the rock-shaft 6 to rock independently of the sleeve F, but compel it to move with such sleeve when the latter is shifted endwise, it being observed, however, that with the arrangement shown the cut-off arm 5 and hub of the crank-arm 17 provide stops or abutments at opposite ends of sleeve F and that the rock-sleeve 18 is obviously not arranged to slide on rod 15.

The devices described for adjusting the cap and cut-off can be duplicated for the other sprinkling device employed, as partially illustrated in Fig. 2, in which the two levers H, one for each sprinkling device, rise through slots in the foot-board and have their lower ends respectively secured to one and the other of a couple of rock-shafts 14. With this arrangement the rock-shafts 14 can be made hollow and can be arranged upon a common rod placed under the foot-board. As a means for locking the adjusting devices the foot-board can be provided with curved racks 22, with which heel-pieces 23 on the foot-rocker can be made to engage by properly tilting such heel-pieces. This arrangement leaves the driver free to direct the team and at the same time permits him to readily lock and unlock the adjusting devices.

To permit the sprinkler-head to be flushed, the cap is provided with a large port 2 and is made of such length that it can be moved back to an extent to open such port, which latter is arranged at a point between the discharge-perforations and the forward end of the cap. The sprinkler-head can therefore be flushed by suitably operating its lever H.

What I claim as my invention is—

1. The hollowsprinkler-head provided with a longitudinally-adjustable, laterally-apertured cap for opening and closing the discharge, and a packing confined between the sprinkler-head and a flanged ring adjustably attached to the sprinkler-head, substantially as described.

2. The hollowsprinkler-head provided with a longitudinally-adjustable, laterally-apertured cap for opening and closing and varying the discharge, and a movable cut-off ar-

ranged external to the cap and applied for further varying the discharge, substantially as described.

3. The hollowsprinkler-head provided with an adjustable, laterally-apertured cap for opening and closing the discharge; a cut-off arranged to slide upon the cap and movable transversely to the length of the latter; and a swinging arm connecting the cut-off with a rock-shaft which extends through the head, substantially as described.

4. A sprinkling device comprising a sprinkler-head provided with a longitudinally-adjustable, laterally-apertured cap for opening and closing the discharge; a cut-off arranged external to the said cap, and mechanism adapted and operative to effect a relative shift on the part of the cap and cut-off for the purpose of varying the width of the spray.

5. The combination with a sprinkling device of a longitudinally-reciprocating or adjustable member for establishing and cutting off the discharge, and a rotary reciprocating cut-off connected with a rock-shaft which extends through the sprinkler device, substantially as and for the purpose described.

6. The combination with a sprinkling device of a longitudinally-reciprocating member for establishing and cutting off the discharge, and a rotary cut-off adapted and arranged to vary the width of the spray.

7. In a sprinkling device, the combination of a rod and sleeve arranged to extend through the sprinkler-head and one of which is connected with the means for establishing and cutting off the discharge and the other of which is connected with the means for varying the width of the spray; means for shifting the rod and sleeve in unison for the purpose of establishing or cutting off the discharge; and means for effecting a relative shift on the part of the rod and sleeve for the purpose of varying the width of the spray.

8. In a sprinkling device, a couple of discharge-controlling members shiftable in unison for the purpose of establishing or cutting off the discharge, and shiftable relatively for the purpose of varying the width of the spray; and a rod and sleeve suitably connected with said members, and by which the latter are shifted for the purpose of regulating the discharge.

9. In a sprinkling device, a couple of discharge-controlling members which are shiftable longitudinally and in unison for the purpose of establishing and cutting off the discharge, and which are shiftable relatively and transversely for the purpose of varying the width of the spray; and a rod and rock-sleeve which are suitably connected with the said members, and by which the latter are shifted for the purpose of regulating the discharge.

10. The combination with the hollowsprinkler-head, and the laterally-apertured, adjustable cap, of a longitudinally-movable sleeve extending through the head and secured to the cap; an externally-arranged cut-off for

varying the discharge; and a rock-shaft connected with the cut-off and extending through the sleeve, said rock-shaft being also capable of longitudinal movement in unison with the sleeve when the latter is moved longitudinally to adjust the cap, substantially as described.

11. The combination with a sprinkler device provided with an apertured movable member for opening and closing the discharge and for varying the same, and a cut-off for further varying the discharge; of a lever connected with the apertured member by power-transmitting connection to operate the same; and a rocker on said lever connected with the cut-off by power-transmitting mechanism as a means for operating such cut-off, substantially as described.

12. The combination of a lever H provided with a rocker, of a rock-sleeve connected with and operated by the rocker; a connecting-rod

extending through the sleeve and connected with said lever; and a sprinkling device comprising a sprinkler-head, a laterally-apertured cap, a sleeve connected with the cap and also connected with said connecting-rod; a cut-off for varying the discharge, and a rod extending through the sleeve which is attached to the cap and connected with said rock-sleeve, substantially as described. 30

13. The combination with a sprinkling device having adjustable members for controlling the discharge, of operating means comprising a lever for operating one member and a rocker on said lever for operating another member, and a rack with which the rocker can be caused to engage, substantially as described.
